UNITED STATES PATENT OFFICE.

CHARLES L. DEPOLLIER, OF NEW YORK, N. Y.

EXPANSION-LINK CATCH-HOOK AND CLASP.

1,088,550.

Specification of Letters Patent.

Patented Feb. 24, 1914.

Application filed July 2, 1913. Serial No. 776,990.

To all whom it may concern:

Be it known that I, CHARLES L. DEPOLLIER, a citizen of the United States, residing in the city of New York, county of Kings, 5 and State of New York, have invented certain new and useful Improvements in Expansion-Link Catch-Hooks and Clasps, of which the following is a specification.

This invention in expansion link catch hooks is directed more particularly to jewelry, and to that class involving link mechanism particularly expansible link bracelets. Germane to the construction of bracelets of this character, my invention involves the expansible link mechanism in providing not only the contractible and expansible link connections between several links of the involved structure, but a terminal catch hook fastening and clasp therefor, whereby the 10 links may be united and locked together with the greatest of facility, while the securing of the coupling and locking device against accidental displacement is assured.

The object of my invention is to provide 25 an expansion link catch hook and clasp therefor, whereby, the coupling together of the link and a ring or bow, connected with another article of jewelry, a pendant, or another similar link may be effected with the 30 greatest of facility, while at the same time, the utmost of security is afforded, as well as simplicity in construction and neatness in design is attainable.

The features which characterize my invention, whereby the objects thereof are secured, are disclosed in the drawings and correlative appended descriptive matter, forming part of this specification, while the novelty thereof is pointed out in the concluding 40 claims thereof.

With reference to the drawings: Figure 1 is an enlarged sectional elevational view of one of my improved expansion link catch-hooks and clasps, taken on the line 4—4 of 45 Fig. 4, and illustrating the expansion link in a contracted condition, and the catch hook and clasp therefor, shown in an engaged, and relatively disengaged condition; the latter being indicated by broken lines. In this 50 view, I have indicated, fragmentarily, the engagement of additional elements, coupled with the link terminal, as well as the manner of coupling an element with the opposite terminal, as afforded by the catch hook and 55 clasp. Fig. 2 is an enlarged side elevational view of the expansion link catch hook and

clasp in an extended condition, together with a fragment of the outline of the surface upon which the catch hook normally rests when in use, as indicated by the curved broken line α — α . Fig. 3 is a similar view to that of Fig. 2, illustrating the catch hook and clasp in a condition for the release thereof. In these figures, a portion of the catch-hook clasp structure, nearest the observer, is illustrated as being removed, leaving a part thereof in sectional elevational view, in order to elucidate the clasp feature of the catch-hook therewith. Fig. 4 is a plan view of the catch-hook, as 70 observed from that side which bears against its resting surface. Fig. 5 is a plan view, taken from the opposite side thereof.

In the several figures, similar characters of reference designate like or the same parts throughout where they occur, wherein,

1 refers to an expansion link, which is composed of longitudinally curved lateral link plates 2 and 3 laterally spaced parallel by a shouldered stud 4, engaging the corresponding ends 5 of each of the said plates, and an integral lug 6 bent up at right angles from the plate 2 at the opposite end 7 thereof, and secured to the corresponding end 8 of the plate 3, together with an inclosed 85 sliding link 9, housed between the link plates 2 and 3, and a similarly inclosed expansion spring 10.

The link plates 2 and 3 are of similar construction and formation, and are each provided with a longitudinally disposed and centrally located rectangularly grooved guide-way 11, having a similar curvature to that of the said link plate. This guide-way is formed by a milling, or other suitable 95 similar operation, by cutting into the inner surface from the end 7 and the end 8 of each of the link plates 2 and 3 and extending the cut along the said link plates for substantially three quarters of the length thereof, 100 whereby, the guide-ways 11 in each of the plates 2 and 3, are brought opposite to each other when the said link plates are assembled, providing at the one end, an entrance to the said guide-way, and at the other, a 105 terminus or stop, common to each of the link plates 2 and 3. Prior to the formation of the integral lug 6 however, by bending the said lug up at right angles from the end 7 of the plate 2, the integral lug 6 will take 110 the place of the end 7 during the operation of forming the guide-way 11. In conse-

quence thereof, the lug 6, when bent up at right angles, has a notch 12, corresponding to the guide-way 11.

The sliding link 9 is formed preferably of a bent strip of flat wire, folded about a guide-pin 13, to provide two laterally spaced parallel longitudinally curved walls 14 and 15. The former terminates abruptly, slightly beyond the lug 6, while the latter extends sufficiently beyond this point, to provide the necessary material for the formation of an eye 16, which latter is formed by the operation of bending the wire, of which the link 9 is formed, about a pin, as for example, 17. After the eye 16 has been suitably formed, it is secured to the wall 15, by soldering the free end thereof to the wall, as designated at 18. Opposite to this soldered joint 18, and on the exterior of the eye 16, the free end of the wall 14 is secured, by a soldered joint 19. The guide-pin 13 is secured intermediately and transversely to the inner end wall of the sliding link 9, by a soldered joint 20. This pin has sufficient length to traverse the sliding link 9 and bottom in the guide-way 11 of each of the link plates 2 and 3, and is of a diameter essential to the provision of a sliding running fit in the said guide-way 11.

Thrusting between the guide-pin 13 and the integral lug 6, is the expansion spring 10. The office of this spring is to thrust the guide-pin 13 in a direction away from the lug 6, until the said guide-pin is brought to a stop by abutting the terminal of the guide-way 11 in each of the link plates 2 and 3, carrying with it, the sliding link 9, and at the same time, bringing the eye 16 into abutment with the integral lug 6. The link plates 2 and 3 are cross-connected and laterally spaced by a bridge 21 in addition to the support afforded by the shouldered stud 4 and integral lug 6. The bridge 21 rises vertically over the sliding link 9, and is integrally connected with, and projecting from the corresponding edges of the link plates 2 and 3 substantially midway of the length thereof. This comprises lateral walls 22 and 23, and an outer wall 24. The walls 22 and 23 are integrally connected with the outer wall 24, which latter is longitudinally and intermediately slotted, to provide a guide-way 25. This has its entrance at a mouth 26, and its terminus at a stop 27. The bridge 21, comprising the lateral walls 22 and 23, and the outer wall 24, is positioned in the manner of an arch over the sliding link 9 and the link plates 2 and 3, and may be connected with the latter by either soldering them together, or by forming the said link plates together with the bridge from a single strip or blank, and subjecting the said strip or blank to the necessary operations in a punch and die-press, to blank the plates 2 and 3, as well as the bridge 21,

and longitudinally and intermediately fold or bend the resultant blank to the required formation, which will bring the link plates 2 and 3 parallel with each other, and at the same time, give the proper formation to the bridge 21, in order that it may be spaced from and arched over the link 9.

Pivoted to a pin 17, which is passed through the eye 16 of the link 9, is a catch-hook 28. This is provided with a laterally spaced pair of integral ears 29, and fitted to telescopically engage the ends of the walls 14 and 15 of the link 9, adjacent to the eye 16 whereby freedom of motion during the oscillation of the hook 28 and the ears 29, upon the pin 17 is afforded. The catch-hook 28 takes a bent formation from the integral ears 29 in a direction toward the line $x-x$ of Fig. 2, to form a loop 30, from whence it is extended, and curved downwardly, to pass under the bridge 21, and beyond the stop 27 thereof. The free end of the hook 28 has an integral jaw 31, which rises vertically to engage and abut the stop 27, and of a height which will enable it to pass slidely under the bridge 21, as will be hereinafter more fully explained.

The operation of my improved expansion link catch-hook and clasp is effected by pulling the hook 28 in the direction of the dart, indicated in Fig. 1, until the said hook assumes the position depicted in Fig. 2, when the jaw 31 shall have been brought abruptly against the stop 27. The effect of this arrests any further movement in the expansion of the device, until the hook 28 is swung by its ears 29 upon the pin 17 in a direction to bring the jaw under the bridge 21, whereupon, continuing the extension, the said jaw may be brought to a position beyond the bridge 21 and swung away therefrom by swinging the hook 28 upon the pin 17 and relaxing the tension, or by pulling upon the said hook, until it assumes the position as indicated by the broken lines of Fig. 1. With the hook 28 thus unclasped or disengaged from the bridge 21, an article of jewelry, as for example, a ring or bow, or other coupling member, may be introduced to the loop 30 by passing it under the hook 28. This is effected by positioning the coupling member upon the bridge 21 and across the guide or slot 25 thereof and under the jaw 31, and by a sliding movement, positioning it between the ears 29 and the end of the loop 30, as depicted in the broken line fragmentary view of the coupling member and the hook 28. After the coupling member, or other article has been thus positioned in the loop 30, the hook 28 is again pulled in the direction of the dart, as indicated in Fig. 1, until the jaw 31 clears the bridge 21, whereupon the former is thrust under the latter to assume the position illustrated in Fig. 3. In this position of the

jaw 31, with respect to the bridge 21, the hook 28 is subjected to a strain at the loop 30, whereby it assumes the characteristic of a spring, which gives it an upward thrust 5 and upon releasing the tension by passing the jaw inward beyond the bridge, the said jaw will be thrust upwardly into the guide or slot 25. Upon further relaxation of the tension on the hook 28, the latter becomes 10 engaged with the end of the wall 24 of the bridge 21, while the opposite surface thereof toward the end thereof, and under the jaw 31 bears against the wall 15 of the link 9. After the article of jewelry or coupling 15 member has been introduced to the loop 30, of the hook 28, any pull upon the same, subjecting it to tension, in a direction as indicated by the arrow in Fig. 1, thrusts the outer surface of the hook 28 against the adjacent 20 surface of the end of the wall 24 of the bridge 21, causing the jaw 31 to engage the stop 27 in the manner of a clasp, thereby securely guarding against the dislodgment or uncoupling of the hook 28 and the article 25 with which it is engaged at the loop 30. On the other hand, upon relaxing the tension upon the catch-hook 28 and reversing the direction of the coupling member or article of jewelry, in order to dislodge it from the 30 loop 30, and bring it to a position between the hook 28 and link 9 over the wall 15 thereof, the said hook will become jammed by virtue of its engagement with the opposing wall 24 of the bridge 21; hence, dislodgment in this direction, of the said article, 35 would be obviated.

Expansion and contraction of my improved expansion link catch-hook is effected by the action of the spring 10 taking its 40 thrust against the guide-pin 13 secured to the link 9 at one end of the said spring, while the other end thereof takes its thrust against the integral lug 6 carried by the link plate 2, which slides freely within the 45 link 9. The effect of pulling upon the shouldered stud 4, by a connected link, or other device, and the loop 30 in opposite directions, expands the link and the spring 10 becomes subjected to compression, the lug 50 6 and guide-pin 13 moving toward each other, compressing the spring in the meanwhile, and the reaction thereof, upon releasing the tension on the structure, permits the expansion of the spring and the result-

ant contraction of the links with respect to 55 each other.

It will be understood by the preceding description of my invention that the same provides an expansion link catch-hook and clasp which permits of the coupling together of another similar link, coupling member, or a ring or bow, connected with an article of jewelry with the greatest of facility and ease of manipulation, while at the same time the utmost of security is afforded. Moreover, it is evident that the device is of simple and durable construction, and conduced, in addition, to variety in artistic opportunities, and

Having fully described my invention, I 70 claim as new, and desire to secure by Letters Patent of the U. S.—

1. An expansion link catch hook of the character described comprising a pair of link plates laterally spaced parallel to each other, a slotted integral bridge above and connecting the pair of link plates, a longitudinally inclosed sliding link between said plates adapted to play therebetween, said sliding link formed with an eye at one end 80 thereof, a catch hook pivotally secured to and carried by the sliding link, provided with a terminal jaw, said bridge being provided with a stop adapted to engage with said jaw, and a spring located within said 85 link adapted to thrust against the sliding link and link plates in the contraction of the link structure, substantially as described.

2. An expansion link catch - hook and clasp therefor, comprising a pair of link plates, laterally spaced parallel to each other, a slotted bridge connecting the two, a sliding link located between the said link plates and adapted to play therebetween, a spring within the said link, pressing between the link plates and the said sliding link, an eye at one extremity of the said sliding link, a catch-hook pivotally secured to the eye, provided with a terminal jaw, said jaw being adapted to engage the said 100 bridge.

In testimony whereof, I have signed my name to this specification in the presence of two subscribing witnesses.

CHARLES L. DEPOLLIER.
